UNITED STATES PATENT OFFICE.

ARSENIO SANAMÉ, OF NEW YORK, N. Y., ASSIGNOR OF ONE-HALF TO PEDRO SAUCEDA.

WHEELED TOY.

Application filed October 3, 1927, Serial No. 223,595. Renewed March 14, 1929.

This invention relates to a wheeled toy and has for its object the provision of a toy which is adapted to be wheeled on the ground and which is provided with mechanically operable decorative devices.

Another object of my invention is the provision of a handle for a toy having mechanically operable decorative elements thereon adapted to rotate in different directions 10 when the toy is moved.

Other objects will appear hereinafter, the novel features and combinations being more clearly set forth in the appended claims.

In the drawings:

Fig. 1 is a perspective view of a toy embodying my invention.

Fig. 2 is a plan view of a wheel of a toy equipped with modified decorative features.

Fig. 3 is a sectional view of a shaft of a 20 toy provided with modified operable decorative devices.

Fig. 4 is a front elevational view of a toy partly in section illustrating a modified form of my invention.

Fig. 5 is a side elevational view of a wheel of the toy illustrated in Fig. 4.

Fig. 6 is a front view partly in section of a further modified form of my invention.

Fig. 7 is a side elevational view of a wheel 30 of the toy illustrated in Fig. 6.

Fig. 8 is a front elevational view partly in section of a further development of my invention.

Fig. 9 is a side elevational view of a wheel 35 of the toy illustrated in Fig. 8.

Referring particularly to Fig. 1 of the drawing, the numerals 10 and 11 designate spaced apart wheels which are rigidly mounted on an axle 12. The wheels 10 and 40 11 are provided with radially extended decorative members 13 which are shaped as shown in the drawing in the form of fan elements. Strips of rubber 14 may be attached to the outer side of the member 13 45 so as to be blown outwardly by the wind created as the wheels revolve. The wheels and fan member 13 may be painted with any desired coloring matter and provided with any suitable design.

A shaft 15 is journaled on the axle 12 at 50 its middle portion by a bearing member 16 which is held in a jet position between the spaced apart collars 17 and 18. It should be understood that the axle 12 rotates free- 55 ly in the bearing member 16. A sleeve 19

is rotatively mounted on the inclined shaft 15 and is provided at its lower extremity with a bevel gear 20 meshed with a bevel gear 21 on the axle 12. The sleeve 19 is held in a desired position between the collars 22 and 23 rigidly mounted on the shaft 15. It should be understood that the bevel gear 21 is rotated in unison with the wheels and the axle and that the sleeve 19 is rotated by the bevel gear 21. A pair of wings 21' or 60 other suitable decorative device may be attached to the sleeve and rotated therewith.

In Fig. 2 the wheel is provided with a center disc 24 and radially extending members 25 are disposed between the disc 24 and the 70 rim of the wheel.

In the modified form of my invention shown in Fig. 3, the shaft 15 is provided with a sleeve 19' at its lower end which is journaled on the shaft as above described. 75 The bevel gear 20' is adapted to be meshed with a similar gear mounted on an axle of a toy and the upper end of the sleeve 19' is provided with a gear member 26 having a circular rack on the upper side thereof. 80 Pinions 27 are rotatively mounted on a shaft 28 rigidly mounted on the shaft 15. Pinions 27 are meshed with a circular rack element 29 of an upper sleeve 30 and are adapted to rotate the latter on the shaft 15. The upper end of the sleeve 30 is provided with a circular rack member having teeth thereon meshed with pinion 31 rotatively mounted on a shaft 32 mounted on the shaft 12. The pinions 31 are meshed with another sleeve 33 90 which is rotatively mounted on the shaft 15. A collar 34 is provided on the shaft 15 above the uppermost sleeve 33 and a similar collar 35 is rigidly mounted on the shaft 15 below the lowermost sleeve 18'. It should 95 be understood that the sleeves are retained in position between the collars 34 and 35 and that rotary movement is imparted from one sleeve to another by the interposed pinions. It should also be understood that adjacent sleeves rotate in opposite directions. Decorated wing members 36, 37 and 38 may be mounted on the sleeves 19, 30, and 33, respectively.

In the form of my invention shown in 105 Figs. 4 and 5, the shaft 15 is rigidly attached to a housing 39 which is disposed around the axle 12, the latter being rotatively journaled in the housing 39. The shaft 15 is provided with a sleeve 19 and wings 21' iden- 110

tical to those shown in Fig. 1 and the bevel gear of the sleeve 19 extends through an arcuate slot in an enlargement 40 of the housing 39 and meshes with the bevel gear 21 of the axle 12. It should be understood that as the axle rotates the sleeve 19 is also rotated by the operative connection between the two bevel gears 20 and 21.

A bevel gear 41 is rigidly mounted on the 10 end of the housing 39 and is meshed with a bevel gear 42 journaled on one of the spokes 43 of the wheel 44. It should be understood that each spoke of the wheel as shown in Fig. 5 is provided with a bevel gear 42 which 15 meshes with the bevel gear 41 of the housing and that both wheels of the toy are similarly equipped. A sleeve 45 is journaled on the spokes 43 and is rigidly attached to the bevel gears 42. It should be understood 20 that as the wheels 44 rotate the sleeves 45 also rotate and that such sleeves may be provided with a plurality of decorative elements such as wings 46. Thus the decorative members of the shaft 15 and the decorative members 25 of the spokes rotate as the wheels 44 are rotated.

In the modified form of my invention illustrated in Figs. 6 and 7, solid discs 47 are employed as wheels and are rigidly attached 30 to the axle 12. A plurality of smaller discs 48 are rigidly mounted on shafts 49 journaled in apertures of the disc wheel 47. Pinions 50 are rigidly mounted on the inner ends of the shaft 49 and are adapted to mesh 35 with a gear 51 rigidly mounted in the housing 39. These little discs 48 may be painted a different color from the disc wheels 47 and may be provided with an irregular design which will be rendered attractive when the discs 48 rotate relative to the disc wheels. It should be understood that the disc wheels 40 of Figs. 6 and 7 may be employed with the shaft mechanism of Fig. 1 or the shaft mechanism of Fig. 3 if desired.

In the modified form of my invention shown in Figs. 8 and 9, the disc wheel 52 is similarly rotated on an axle 12 which is provided with a housing 39 having a gear 51 thereon. A ring member 53 is mounted on 50 the outer surface of the disc wheel 52 and is secured in place by roller member 54 which are rotatively mounted on the disc wheel 52. The shafts of the roller members 54 are bent inwardly against the ring member 53 for holding the same in close proximity to the surface of the disc wheel. The inner circumference of the ring 53 is provided with teeth 56 which are meshed with the teeth of a pinion 57. The pinion 57 is rigidly mounted on shaft 58 journaled in apertures in the disc wheel 52. The inner ends of the shaft 58 are provided with pinion 59 which are meshed with the gear 51 of the housing 39. An inner disc 60 is rotatively mounted on 60 the axle 12 and is provided with teeth 61 on

the periphery thereof which are meshed with the teeth of the pinion 57. The above described construction such as will cause the ring 53 and the disc 60 to rotate in opposite directions as the disc wheel 52 is rotated by pushing or pulling the toy along with the disc wheels on the ground.

It should be understood that the rings, discs and disc wheels may be painted in any desired combination of colors, and designs 75 and that any of the wheel members may be employed with either the shaft mechanism of Fig. 1 or of Fig. 3.

Having thus fully described and shown an embodiment of my invention what is desired 80 to be secured by Letters Patent of the United States is:

1. A toy of the class described comprising spaced apart wheels, an axle rigidly attached to said wheels adapted to rotate therewith, 85 a shaft journaled on said axle, intermediate its ends, a housing on said axle connected with said shaft, gears on said housing, decorative sleeve rotatively mounted on the spokes of said wheels, and a gear on each of said sleeves meshing with the gears of said housing for rotating said sleeves relative to said spokes when said wheels and axle rotate relative to said housing.

2. In a toy of the class described the combination with a pair of spaced apart wheels comprising spokes, of an axle attached to said wheels, a housing journaled on said axle, a shaft attached to said housing, a sleeve rotatively mounted on said shaft, a gear on said sleeve, a gear mounted on said axle and disposed in said housing meshed with the gear of said sleeve, a gear on the end of said housing, and sleeves rotatively mounted on said spokes and gears rigidly attached to said last mentioned sleeves and meshed with the gear of said housing for effecting rotation of said last mentioned sleeves when said wheels rotate relative to said housing.

3. In a toy of the class described the combination with a pair of spaced apart wheels comprising spokes, of an axle attached to said wheels, a housing journaled on said axle, a shaft attached to said housing, a sleeve rotatively mounted on said shaft, a gear on said sleeve, a gear mounted on said axle and disposed in said housing meshed with the gear of said sleeve, a gear on the end of said housing, sleeves rotatively mounted on said spokes and gears rigidly attached to said last mentioned sleeves and meshed with the gear of said housing for effecting rotation of said last mentioned sleeves when said wheels rotate relative to said housing and decorated wings mounted on the sleeves of said spokes and the sleeve of said shaft.

4. A toy of the class described comprising an axle, spaced wheels mounted on said axle adapted to rotate therewith, a housing 130

journaled on said axle, a shaft attached to said housing, a plurality of decorative devices rotatively mounted on said shaft and operatively connected together and to said axle adapted to be rotated thereby, a plurality of decorative devices rotatively mounted on said wheels and operatively connected with said housing adapted to be rotated when said axle rotates relative to 10 said housing.

5. A toy of the class described comprising an axle, spaced apart wheels journaled on

said axle, decorative devices rotatively mounted on said wheels, a shaft journaled on said axle, decorative devices journaled on 15 said shaft, and means operatively connecting the decorative devices of said shaft and of the spokes of said wheels adapted to cause rotation thereof when said wheels and axle are rotated.

20 In testimony whereof I have affixed my signature.

ARSENIO SANAMÉ.
